UNITED STATES PATENT OFFICE.

WILLIAM H. FITCH, OF AURORA, ILLINOIS, ASSIGNOR TO RICHARDS-WILCOX MANUFACTURING COMPANY, OF AURORA, ILLINOIS, A CORPORATION OF ILLINOIS.

HANGER FOR FLEXIBLE COVERINGS FOR DOORWAYS, &c.

Patented June 24, 1919.

1,307,440.

Specification of Letters Patent.

Application filed October 7, 1918. Serial No. 257,299.

To all whom it may concern:

Be it known that I, WILLIAM H. FITCH, a citizen of the United States, and a resident of Aurora, in the county of Kane, State of Illinois, have invented certain new and useful Improvements in Hangers for Flexible Coverings for Doorways, &c., of which the following is a specification, reference being had to the accompanying drawings.

10 In many situations it is deemed preferable to close certain doorways by means of devices made of canvas or other similar flexible material instead of by rigid doors slidingly or hingedly secured in place. In connection with the unusually wide doorways of hangars for aeroplanes it is deemed best to employ such canvas or other flexible curtains as they can be swept to one side very quickly and readily to permit the hurried exit of the 15 machine that is frequently necessary. In order to have approximately the same protecting qualities against rain, snow and wind storms as are possessed by metal or wooden doors it is necessary that means be provided 20 for preventing, in large measure at least, the tendency of such flexible closure devices to sway in and out of the doorway. It is also necessary that overhead suspension means be provided of a character that will enable the 25 flexible closure to be so moved that the various suspension means will not interfere with each other as by overlapping or becoming entangled, as frequently is found to be the 30 case where suspension rings attached to an overhead rod are employed for suspending 35 such a closure.

It is the object of my invention to provide a doorway-closing means so suspended that it will not easily sway in the wind and 40 which can be moved easily and quickly toward either side of the doorway without liability of the suspension devices becoming entangled with or overlapping each other. I 45 accomplish this object by the devices and combinations of devices shown in the drawing and hereinafter particularly described. That which I believe to be new will be set forth in the claims.

In the drawings,—

50 Figure 1 is a side elevation of a portion of a curtain of flexible material movably supported by means of my improvements;

Fig. 2 is an end view of the parts shown in Fig. 1, except that the curtain and the hanger-track are shown in section; and 55

Fig. 3 is a cross-section taken at line 3—3 of Fig. 1.

Referring to the drawings,—5 indicates a hollow track of well-known construction, the two edges of which are inwardly turned to 60 form track rails upon which runs a trolley comprising a pair of wheels 6 and a hanger plate 7, which, in the form of construction shown is a plate turned centrally upon itself and having its central portion enlarged and 65 made cylindrical to loosely receive and hold a bolt 8. 9 indicates an apron from the upper edge of which and at opposite sides of its central portion rise two ears 10 that terminate in short sleeve members 11 that surround the end portions of the bolt 8 and which I prefer to clamp tightly to such bolt. The construction described constitutes a 70 hinge connection between the trolley and the apron. The central portion of the apron is 75 bowed outwardly to form a semi-cylindrical socket, and the ends of the apron are turned out at substantially right angles to form end flanges 13. 14 indicates a clamping plate of substantially the same size and shape as the 80 apron 9, except that such clamping plate is not provided with ears and sleeves corresponding to the ears and sleeves 10 and 11 of the apron. The plate 14 has a central outwardly bulged or bowed portion 15 corresponding to the portion 12 of the apron 9, 85 said portions 12 and 15 together constituting a socket for clamping a pole between them, as hereinafter described. The end portions 90 of the plate 14 are turned outwardly in the same direction as the central bowed portion 15 to form end flanges 16. 17 indicates a pole preferably made of wood, the upper end of which is inserted in the socket formed by the bowed members 12 and 15 and securely 95 clamped therein by means of bolts 18 passing through openings near the ends of said parts 9 and 14, upon which bolts tightening nuts 19 are screwed.

20 indicates a curtain of canvas or other suitable material secured in any suitable manner at intervals along the length of the pole and having its upper edge extending up to substantially the upper edge of the

clamping member 14, as indicated, the upper portion of such curtain lying also between the parts 9 and 14, as clearly shown in Fig. 3, and being provided with holes 5 through which the several bolts 18 pass, the holes in the curtain being preferably provided with eyelets 21.

I contemplate connecting to each end of the curtain a supporting device such as shown, including a pole 17 and as many such devices and poles intermediate the ends of the curtain as may be required. In the illustration a portion of the curtain intermediate of its length is shown, and hence 15 such curtain thus passes partially around the pole and to which it may be secured below the members 9 and 14 by tacks, screws or other fastening means. At its ends the curtain may be wrapped to a greater or less extent around the end poles as may be desired. While I have shown the pole-receiving sockets and the poles as being cylindrical, I do not confine myself to such shape as it is evident that they may 20 be differently shaped without departing from the spirit of my invention.

With curtains hung according to my improvements it is evident that they will be securely and evenly clamped along their 30 upper edge to the depending aprons that are hingedly connected to the trolleys and that they can be pushed to one side very readily owing to their bending or buckling to one side or the other between the various sets 35 of clamping devices, and by reason of the smooth running of the trolleys in their overhead tracks. Furthermore, by reason of the oppositely-turned flanges 13 and 16 carried by the apron and the clamping plate, 40 respectively, wide contacting or bearing surfaces are provided at each end of the clamping means which will come in contact with the similar turned ends of the next adjacent clamping means and thus effectually prevent any entanglement of one device with another, so that when the curtain is again moved in the reverse direction to close the doorway such movement can be 45 had as readily and quickly as in the opening. The depending poles, which extend the full width of the curtain,—that is, from near the top of the doorway to near the bottom thereof—impart sufficient weight to the curtain so as to hold it down and in proper 50 place and counteract to a large extent any tendency to sway in or out of the doorway. The poles have been described as being wooden poles and I prefer to so make them, but it is, of course, evident that they might 55 be made of other material such as light steel tubes or rods, and if so made appropriate changes would have to be made in the means 60

for fastening the curtains along the length of such poles.

What I claim as my invention and desire 65 to secure by Letters Patent, is—

1. A hanger comprising in combination an overhead trolley, an apron hinged thereto and depending therefrom and forming one member of a clamp, a second clamp 70 member opposite said apron, each of said members having an outwardly-bowed portion which when opposite each other form a vertical socket, and means at each side of such socket for tightly clamping said members together. 75

2. A hanger comprising in combination an overhead trolley, an apron hinged thereto and depending therefrom and forming one member of a clamp, a second clamp 80 member opposite said apron, each of said members having an outwardly-bowed portion which when opposite each other form a vertical socket and each of said members having its ends turned in the same direction 85 as its socket portion, and means at each side of said socket for tightly clamping said members together.

3. The combination with an overhead trolley, of an apron hinged thereto and depending therefrom and constituting one member of a clamp, a second clamp member opposite said apron, a pole having its upper portion between said clamp members, a flexible curtain having its upper marginal 95 portion between said members and connected with said pole, and means at each side of said pole for drawing said clamping members toward each other. 90

4. The combination with an overhead 100 trolley, of an apron hinged thereto and depending therefrom and constituting one member of a clamp, a second clamp member opposite said apron, a pole having its upper portion between said clamp members, 105 a flexible curtain having its upper marginal portion between said members and between one of said members and the pole, and means at each side of said pole for drawing said clamping members toward each other. 110

5. The combination with an overhead trolley, of an apron hinged thereto and depending therefrom and constituting one member of a clamp, a second clamp member opposite said apron, each of said members having an outwardly-bowed portion which when opposite each other form a vertical socket, a pole having its upper portion between said clamp members, a flexible curtain attached to said pole, and means at 115 each side of said vertical socket for drawing said clamping members toward each other and against the pole. 120

WILLIAM H. FITCH.
